UNITED STATES PATENT OFFICE.

ALEXANDER COPLAND ROBERTSON, ALEXANDER COLIN MURRAY, AND WILLIAM WALTER SMITH, OF TIMARU, NEW ZEALAND, ASSIGNEES TO THE ROBERTSON MARINE ENGINE BRAKE COMPANY, LIMITED, OF TIMARU, NEW ZEALAND, A CORPORATION OF NEW ZEALAND.

APPARATUS FOR CONTROLLING THE SPEED OF STEAM-ENGINES.

1,184,213.

Specification of Letters Patent.

Patented May 23, 1916.

Application filed December 19, 1911. Serial No. 666,652.

To all whom it may concern:

Be it known that we, ALEXANDER COPLAND ROBERTSON, ALEXANDER COLIN MURRAY, and WILLIAM WALTER SMITH, all citizens of the 5 Dominion of New Zealand, and residing at Timaru, in the Provincial District of Canterbury, Dominion of New Zealand, have invented certain new and useful Improvements in Apparatus for Controlling the Speed of 10 Steam-Engines, of which the following is a specification.

This invention relates to apparatus used for controlling the speed of steam engines, motors and other machinery and provides 15 improved apparatus for this purpose. According hereto, a brake strap is made in two parts hinged together at the front, and carries brake blocks surrounding or partially surrounding the main shaft or a pulley fixed upon the said shaft. The hinge pin passes through brackets and forms a pivot for the brake strap. The rear ends of the 20 strap are pivoted to levers fulcrumed in brackets, and having their ends coupled by 25 links to a crosshead, which is fixed to a piston rod.

In a modification, the brake blocks are not mounted on a strap as described, but are connected directly to the levers.

30 The crosshead slides upon a guide bar fixed at one end to the cylinder and at the other end to the brackets of the lever. A governor receiving motion from the main shaft has its spindle connected by a bell 35 crank lever to a valve for admitting, in the case of a steam engine, steam to the back of the piston, and a bracket projecting from the crosshead operates a relief valve to allow the piston to make its return stroke. When 40 the shaft attains a predetermined speed, the governor operates its valve to admit steam to the rear end of the cylinder, the piston is forced forward and the brake is applied, and the relief valve is operated to admit 45 steam to the front end of the cylinder, and to equalize the pressure on the two sides of the piston.

The effect of admitting steam to the front 50 end of the cylinder, after the brake has been applied by steam at the rear end of the cylinder, is to keep the pressure of the brake fully applied to a predetermined extent and no more, while the steam at the front end of

the cylinder is ready to release the brake instantaneously when the pressure of the steam is reduced at the rear end of the cylinder by exhausting the steam at the said rear end. 55

When the speed of the shaft is reduced to normal, the governor cuts off steam from, and opens the exhaust at the rear end of the 60 cylinder, thus allowing the pressure at the front of the cylinder to force the piston back and release the brake. The return of the bracket on the crosshead closes the relief valve and opens its exhaust, and the mechanism 65 is then in position for acting again.

Compressed air, water under pressure or vacuum can be substituted for steam power.

The drawing herewith illustrates the invention as adapted to be operated by steam. 70

Figure 1, is a side elevation, and Fig. 2, is a plan of the apparatus, Fig. 3, is a sectional plan of the cylinder on line A—A, Fig. 1. Fig. 4, a cross section on line B—B, Fig. 1, Fig. 5, a side elevation of regulating mechanism, Fig. 6, a cross section on line C—C, Fig. 5, Fig. 7, an elevation of brake shoes attached directly to levers. 75

The brake strap, as shown in Figs. 1 and 2, comprises an upper part 1 and lower part 2 80 hinged together upon a pin 3 pivoted in a bracket 4. The brake is provided with friction blocks 5 surrounding a drum 6 fixed to the shaft 7, which it is desired to control. In some cases the blocks are applied directly to 85 the shaft instead of to a drum as just described. The rear end of the straps 1 and 2 are pivoted to levers 12 and 13 fulcrumed by pins 14 and 15 upon brackets 16. The rear ends of the levers 12 and 13 are coupled by 90 links 17 and 18 to a crosshead 19 fixed upon the end of a piston rod 20, and guided by bars 21.

Fig. 7 shows brake shoes 22 and 23 pivoted by pins 24 and 25 directly to levers 12 and 13, 95 the brake strap being dispensed with.

The piston 30 of the rod 20 works in a cylinder 31. A steam valve 32 slidable in the valve chest 33 has a head 34 adapted to close a port 35 opening to a steam supply 100 pipe 36 and a port 37 opening to the cylinder 31, when the balls of the governor 38 are closed together. At the same time a groove 41 in the valve places an exhaust port 42 in the cylinder in communication with an exhaust port 43 in the valve chest. When the 105

shaft 7 has attained a predetermined speed the governor 38 operates its spindle 44 and raises the valve 32 by means of the bell crank lever 45. Steam passes from the port 35 around the groove 41 and through the port 37 to the rear end of the cylinder 31 and forces the piston 30 forward. The links 17 and 18, which with the levers 12 and 13 form a toggle are operated and the brake 10 applied to the drum 6. The bracket 46 projecting from the crosshead 19 carries a screw threaded rod 51 adjustable by means of lock nuts 47 and 48. A bell crank lever 49 fulcrumed on a pin 50 is coupled at one 15 end to the rod 51 and at the other end to the spindle 54 of a relief valve 55 constructed and adapted to close ports similar to the valve 32. The opening of the relief valve 55 admits steam to the forward end of the cylinder 31, and thereby makes the pressure at the front of the piston equal to the pressure at the back thereof.

The application of the brake reduces the speed of the shaft, and the governors reverse the operation of the valve 32 to exhaust the steam from the rear side of the piston. The pressure at the front of the cylinder forces the piston rearwardly, and the lever 49 being released by the return stroke of the bracket 46, the relief valve 55 opens to the exhaust and allows the steam to escape from the front of the cylinder. The parts are thus restored to their original positions and condition ready for re-operating.

Referring now to Figs. 5 and 6, the spindle 44 is shown with a slot 60, having upon one side a rack 61, wherewith meshes a pinion 62 fixed to the spindle 63 of a hand wheel 64. The slotted end member 65 of the rod is connected to the spindle proper 44 by a joint 66. The face of the spindle is marked with a scale 67, the numbers whereon indicate the number of revolutions 45 or the miles per hour at which the shaft is set to work. By operating the hand wheel and adjusting the spindle 44 in relation to the bell crank lever 45 the speed of rotation is varied as desired. The hand wheel 64 and pinion 62 are locked by means of a spring 50 operated bolt or slide 70 having an operating handle 71. The bolt is adapted to engage slots 72 formed around the circumference of a disk 73 fixed to the end 65 of the spindle 44.

When atmospheric pressure is employed to operate the brake, the construction is precisely similar to the construction used when steam is employed as the motive power, with the exception that the exhaust port 43 in the case of both valves 32 and 55 is connected by a pipe to an air exhauster of any ordinary construction.

The operation is then as follows:—The valve 32 opens the back of the cylinder to

the air exhauster and the valve 55 opens the front of the cylinder to the exhauster, thus placing the piston in equilibrium. The governor operates the valve 32 when the predetermined speed has been attained, thereby opening the back of the cylinder to atmospheric pressure and shutting off the air exhauster, the brake being thereby applied. The relief valve 55 is operated by the movement of the crosshead as previously described, and the front of the cylinder opened to the atmosphere while the opening of the exhauster is closed. Upon the speed of the shaft being reduced the governor returns the valve 32 to its original position by the return movement of the crosshead, thus all parts are restored to their original positions.

An arm 80 fixed to the governor spindle 44 engages the lower end of a lever 81 pivoted at 82, and the upper end of this lever has a slot 83 engaging a pin 84 projecting from a block 85 slideable in a guide 86 carried by the frame 78. A spindle 77 mounted in this frame 78 carries a drum 76 on which a suitably marked sheet of paper 90 may be arranged, said spindle being rotated by suitable chronometer mechanism (not shown). The block 85 carries a pencil or other marking instrument, which records on the paper sheet the number of revolutions or speed of the engine.

What we do claim and desire to secure by Letters Patent of the United States is:—

1. Apparatus of the nature indicated, comprising in combination, a fluid pressure cylinder, a piston therein, braking means operable by said piston, a governing device actuated according to the speed of the machinery to be controlled, means controlled by said governing device for admitting fluid to said cylinder, on one side of said piston, to cause actuation of said braking means, and means operated by said piston for automatically admitting fluid to said cylinder on the other side of said piston, after a predetermined movement of the piston.

2. Apparatus of the nature indicated, comprising in combination, a fluid pressure cylinder, a piston therein, braking means operable by said piston, a governing device actuated according to the speed of the machinery to be controlled, means controlled by said governing device for admitting fluid to said cylinder on one side of said piston, to cause actuation of said braking means, and adjustable means operated by said piston for automatically admitting fluid to said cylinder on the other side of said piston, after a predetermined movement of the piston.

3. Apparatus of the nature indicated, comprising in combination, a fluid pressure cylinder, a piston therein, braking means operable by said piston, a governing device actuated according to the speed of the ma-

chinery to be controlled, means controlled by said governing device for admitting fluid to said cylinder, on one side of said piston, to cause actuation of said braking means, and valve means operated by said piston for automatically admitting fluid to said cylinder on the other side of said piston, after a predetermined movement of the piston.

10 4. Apparatus of the nature indicated, comprising in combination, a fluid pressure cylinder, a piston therein, braking means operable by said piston, a governing device actuated according to the speed of the machinery to be controlled, adjustable means controlled by said governing device for admitting fluid to said cylinder, on one side of said piston, to cause actuation of said braking means, and means operated by said piston for automatically admitting fluid to said cylinder on the other side of said piston, after a predetermined movement of the piston.

5. Apparatus of the nature indicated, comprising in combination, a fluid pressure cylinder, a piston therein, braking means operable by said piston, a valve for controlling the admission of fluid to said cylinder on one side of said piston, a rod connected to said valve, a lever connected to said rod, a second rod adjustably connected to said lever, and a governing device actuated according to the speed of the machinery to be controlled, said device operating through said rods and lever to control said valve.

6. Apparatus of the nature indicated, comprising in combination, a fluid pressure cylinder, a piston therein, braking means 40 operable by said piston, a governing device

actuated according to the speed of the machinery to be controlled, means controlled by said governing device for admitting fluid to said cylinder on one side of said piston, to cause actuation of said braking means, a lever connected to said means, a pinion carried by said lever, a rack connected to said governing device and meshing with said pinion and means for rotating said pinion on said rack, to adjust the lever relatively to the governing device. 45 50

7. Apparatus of the nature indicated, comprising in combination, a fluid pressure cylinder, a piston therein, a crosshead connected to said piston, braking means operable by said crosshead, a governing device actuated according to the speed of the machinery to be controlled, means controlled by said governing device for admitting fluid to said cylinder on one side of said piston, to cause actuation of said braking means, a rod adjustably connected to said crosshead, a pivoted lever connected at one end to said rod, and a valve connected to the other end of said lever for admitting fluid to said cylinder on the other side of said piston. 55 60 65

In testimony whereof we have signed our names to this specification in the presence of two witnesses.
